Primary Examiner — Barbara Fox*Assistant Examiner* — Harold E Blackwell, II(57) **CLAIM**

The ornamental design for a wrench storage rack, as shown and described.

DESCRIPTION

FIG. 1 is a front, left and top perspective view of a wrench storage rack showing our new design;

FIG. 2 is a perspective view of the wrench storage rack of FIG. 1 with a front cover is opened;

FIG. 3 is a front, right and top perspective view of the wrench storage rack of FIG. 1 in a usage state;

FIG. 4 is a front view thereof;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

The broken lines in the figures illustrate portions of the wrench storage rack that form no part of the claimed design. The broken lines in the FIG. 3 illustrate wrenches that form no part of the claimed design.

1 Claim, 9 Drawing Sheets(56)
